UNITED STATES PATENT OFFICE.

CHARLES F. PORTER, OF NEW YORK, N. Y.

HAIR-DRESSING FOUNDATION.

1,160,956.

Specification of Letters Patent. Patented Nov. 16, 1915.

Application filed March 25, 1915. Serial No. 16,823.

To all whom it may concern:

Be it known that I, CHARLES F. PORTER, a citizen of the United States of America, and a resident of the borough of Manhattan, 5 city, county, and State of New York, have invented certain new and useful Improvements in Hair-Dressing Foundations, of which the following is a specification.

This invention relates to foundations for 10 hair dressing, and particularly to the type of foundation wherein the strands of hair are clasped together and means is provided for supporting the coils of the hair away from the head.

One object of my invention is to provide 15 a clasp for holding the strands of the hair together at a point spaced from the head and to hold the portion of the hair so clamped together in a position fixed relatively to 20 the head.

Another object of my invention is to provide 25 a foundation for hair dressing which will hold the strands of hair together at one point and upon which the coils of hair may be supported so that they are spaced 30 from the head to permit a circulation of air, whereby a ventilation of the hair is provided.

Other and further objects and advantages 35 of my invention whereby a low cost of manufacture is possible and a simple practical device is provided will appear from the following description taken in connection with the drawings which form a part of this specification and will be pointed out in the claims hereinafter appended.

In the drawings, Figure 1 illustrates the manner in which a device embodying my invention is to be employed; Fig. 2 is a plan 40 view of the device in unclasped position; Fig. 3 is a similar view in clasped position; Fig. 4 is a side view of the device in the position shown in Fig. 2.

It has been found highly desirable to support the coils of hair at a point removed 45 from the head, in order that the circulation of air may ventilate the scalp, and, to this end, the device herein described as embodying my invention includes a base 1, which is 50 preferably formed of resilient material, such as wire, and which comprises a substantially circular loop, the ends 2 of which are positioned near to one another. To the ends 2 of the loop 1 there is attached an open-ended 55 loop 3, the sides 4 of which are bowed toward one another and lie normally near to

one another when the device is in the so-called unclamped position. From a point on the base loop 1 diametrically opposite from the point where the open-ended loop is 60 attached, a supporting member 5 extends up to and is attached to the closed end 6 of the loop 3. From points on the circumference of the base loop 1, other supporting members 5 extend up to and are attached to 65 the supporting member 5' by being wrapped around said member 5'. The open-ended loop 4 and the supporting members 5 and 5' extend up above the plane of the base 1, as indicated in Fig. 4. At the point where 70 one of the members 4 is attached to the end 2 of the base loop 1, a coil 7 is formed, and the ends 2 of the loop 1 are sprung together, and the other part 4 of the loop 3 is engaged or clasped by the said loop 7. 75

The wire or other material of which this hair dressing foundation is formed is preferably covered with a wrapping of thread or other similar material, in order to make it less conspicuous and of the proper color. 80

In using this hair dressing foundation, the strands of hair are slid in between the sides 4 of the open-ended loop 3, and the ends 2 of the base loop 1 are sprung together, and one of the sides 4 is clasped by 85 the loop 7. The hair is thus clasped together at a point spaced from the head, for the base 1 rests upon the head and the clasp is spaced from the base of the device. The hair may now be coiled about the foundation, and it 90 is seen that it is supported away from the head to provide ventilation.

While I have described a particular embodiment of my invention with great detail, I do not desire that my invention shall be 95 limited to the specific features described, but intend that it shall be defined by the scope of the claims hereinafter appended.

What I claim and desire to secure by Letters Patent of the United States is the following:— 100

1. In a hair foundation, a base comprising a loop of resilient material having its ends juxtaposed and a clasp comprising a loop adapted to inclose the hair within it 105 secured to the ends of said base loop.

2. In a hair foundation, a base comprising a loop of material having its ends juxtaposed, a loop of resilient material having its ends respectively joined to the ends of the 110 first-named loop and means for detachably securing the ends of said base together.

3. In a hair foundation, a base comprising a loop of material having its ends juxtaposed, a loop of resilient material having its ends respectively joined to the ends of the first-named loop and means for securing the sides of said second named loop together at a point removed from the closed end of said loop. 5
4. In a hair foundation, a base comprising a loop of material having its ends juxtaposed, an open loop of resilient material having its ends respectively connected to the ends of the first-named loop and means for detachably securing the points of connection together to close both loops. 10
5. In a hair foundation, a base comprising a loop of material having its ends juxtaposed and a second loop having its ends respectively connected to the ends of the first-named loop, the points of connection being formed to interengage one with the other and one of said loops being resilient whereby said points of connection are held into interengagement. 20
6. In a hair foundation, a base comprising a loop of material having its ends juxtaposed and a loop of resilient material having its ends respectively joined to the ends of the first-named loop, said last-named loop lying in a different plane from said base loop and being adapted to clasp the hair within it. 25
7. In a hair foundation, a base comprising a loop of material having its ends juxtaposed and a second loop of resilient material having its ends respectively joined to the ends of the first-named loop, the joined portions being formed to interengage and one of said loops being resilient whereby said portions are held into interengagement, 30 said second loop lying in a different plane from said base loop. 35
8. In a hair foundation, a base comprising a loop of material having its ends juxtaposed and a second loop of resilient material having its ends respectively joined to the ends of the first-named loop, said second loop lying in a different plane from said base loop, and means extending from said base loop to hold said second loop in 40 position and provide support for the hair. 45
9. In a hair foundation, a base comprising a loop of material having its ends juxtaposed, an open loop having its ends respectively joined to the ends of the first-named loop, one of said loops being resilient and one of said loops being adapted to encircle the hair whereby the ends of both loops are held juxtaposed and the strands of hair are clasped together between the sides of one 50 loop. 55

In testimony whereof, I have signed my name to this specification.

CHARLES F. PORTER.
